LOCOMOTIVE STRUCTURE

Karl S. Howard, Philadelphia, Pa., assignor to
General Steel Castings Corporation, Granite
City, Ill., a corporation of Delaware

Application March 16, 1932. Serial No. 599,292

19 Claims. (Cl. 105—44)

This invention relates to railway rolling stock and consists in a novel locomotive underframe construction and particularly in the arrangement of exhaust steam piping and smoke box supports.

Heretofore it has been the usual practice in locomotive construction to support the front end of the boiler or smokebox upon a rigid saddle member projecting upwardly from the underframe. The cylinders and valve chambers are frequently cast integral with the saddle and are located substantially in transverse alignment therewith. The exhaust pipes extend inwardly and upwardly through the saddle and merge in the upper part thereof in upright passages which connect with the exhaust nozzle inside the smokebox.

Due to the intermittent passage of hot steam through the exhaust passages, the portions of the underframe immediately adjacent the passages are subjected to strains which frequently cause cracks to develop in the casting. In order to relieve the structure of these strains it has been suggested to separate the exhaust pipes on opposite sides from each other and from the cylinder saddle except at the points at which the pipes pass through the side walls of the saddle. Also the arcuate bottom plate of the smokebox has been corrugated or recessed to better adapt the member to withstand expansion and contraction.

Structures utilizing the above features are disclosed in copending applications, Serial No. 541,894, filed June 3, 1931 in the names of E. G. Hallquist and myself, and Serial No. 547,137 filed June 26, 1931 in the name of the present applicant.

The general object of the present invention, as in the above mentioned applications, is to provide improved means for preventing unequal strains from being set up within the cylinder saddle and underframe. I attain this object and others substantially by completely separating the exhaust passages from the smokebox saddle and adjacent underframe structure and also separating the opposing pairs of exhaust pipes from each other. In the drawings which illustrate the invention—

Figure 1 is, in part, a top view of the front end of a locomotive underframe embodying the invention and, in part, a horizontal section taken substantially on line 1—1 of Figure 4.

Figure 2 is a side view of the structure.

Figure 3 is a front view of the same.

Figure 4 is a vertical transverse sectional view taken substantially on the line 4—4 of Figure 1.

Figure 5 is a half horizontal section taken on the line 5—5 of Figure 2.

Figure 6 is a view corresponding with Figure 4 but illustrating a modification.

Figure 7 is a vertical longitudinal section taken on line 7—7 of Figure 6.

Figure 8 is a partial top view of another modification.

Figure 9 is a side view of the same.

Figure 10 is a half front view of the same.

Figures 11, 12, and 13 are top, side, and front views, respectively, of still another modification.

In Figures 1 to 5, inclusive, is illustrated the front end of an integral locomotive bed including box section main frame member 1, front deck structure 17, and pilot beam mounting 18. The top and bottom webs of main frame member 1 are provided at 2 and 3 with laterally extended triangular portions which cooperate with vertical webs 4 and 5 to form a transverse beam extending across the bed for supporting main steam cylinders 6 and valve chambers 7.

Cylinders 6, projecting forwardly from the ends of this transverse beam structure, are spaced from the adjacent portion of the underframe and have integral backheads 8 which merge with vertical web 5. Copending application Serial No. 547,136, filed June 26, 1931, in the name of the present applicant illustrates and describes in detail a locomotive bed having a similar transverse beam and cylinder construction.

A boiler saddle 9 projects upwardly from the bed above the transverse beam structure for supporting the front end of the boiler or smokebox wall 12. Pairs of exhaust pipes 10 extend inwardly from the ends of valve chambers 7 and merge with separate upright passages having 90 bolting flanges 11. The exhaust pipes are spaced forwardly of saddle 9 throughout their lengths and the opposing pairs are also spaced from each other.

The smokebox bottom plate 12 is bulged, as at 20, to provide for properly seating flanges 11 and has a curved portion 13 between the exhaust pipes to accommodate expansion and contraction in the pipes. An inverted V-shaped nozzle 21 is bolted or riveted to flanges 11 and plate 12, the nozzle having bottom flanges 21a for cooperating with flanges 11 to form an air tight joint with the smokebox wall.

Projecting upwardly from each side of deck structure 17 are pump brackets 14 braced by diagonal ribs 15 and 16. A bracket 19 extends between ribs 16 and mounts an expansion plate 20 which supports the front end of the smokebox wall 12.

In Figures 6 and 7, exhaust pipes 22 are located

rearwardly of saddle 27 and extend through an opening 25 in the bottom of the smokebox wall 23, and connecting flanges 24 on the exhaust pipes are made horizontal to simplify the necessary 5 machining operations. A separate recessed plate 26 is secured over opening 25 and is bolted between flanges 24 and the corresponding flanges 28a on the lower ends of inverted V-shaped nozzle 28.

10 In Figures 8 to 10, boiler saddles 29 and 30 are provided on each side of exhaust pipes 31 extending between valve chambers 32. The forward saddle 30 extends between the rear ends of pump brackets 33 and replaces expansion plate 20 in 15 Figures 1 to 5. This modification otherwise conforms with that in Figures 1 to 5.

In Figures 11 to 13, U-shaped exhaust pipes 34 and 35 are formed separately and bolted to the ends of valve chambers 36 and to the lower legs 20 of three way pipe sections 37. The upright legs 25 of pipes 37 connect with the exhaust nozzle, not shown, within the smokebox and which may be of inverted V-shape as in Figure 6. Pump brackets 38 and expansion plate bracket 39 project upwardly from the front deck structure, as in Figures 1 to 5. Brackets 40 for the valve gear combination lever are shown formed integral with pipe 35. These brackets, however, may be secured to adjacent structure in any suitable manner.

30 In each of the forms, the exhaust piping, which is subject to marked fluctuations of temperature due to the intermittent passage of hot steam, is completely isolated from the adjacent underframe and boiler supports so that these parts 35 can not be affected by expansion or contraction in the pipes. Moreover the separation of the pairs of exhaust pipes leading from each valve chamber and the appropriate shaping of the lower portions of the smokebox wall permit un-40 limited lateral expansion and contraction of the exhaust pipes relative to each other.

Obviously various features of the different forms may be interchanged, where desired, and the forms may be modified as to details without 45 departing from the spirit of the invention. Many 50 of the features may be advantageously embodied in a built-up underframe, although the integral structure illustrated is preferable because of the increased strength and decreased weight due to 55 the more advantageous distribution of metal, and the consequent elimination of much of the labor and expense of machining and fitting various joints and the elimination of the necessity of frequent inspection after the locomotive is in service.

The exclusive use of these and such other modifications as come within the scope of the appended claims is contemplated.

What is claimed is:

60 1. In a locomotive underframe structure, a boiler support, spaced valve chambers, and main exhaust steam pipes extending inwardly from said chambers at the level of said support but 65 outside thereof and then upwardly, said passages being spaced throughout their lengths from each other and from the remaining portions of the structure.

2. In a locomotive, an underframe structure 70 including spaced boiler supports and valve chambers at each side of said structure, a smokebox supported by at least one of said boiler supports, and exhaust steam pipes extending between said supports from said chambers to said smokebox, 75 said pipes being spaced throughout their lengths

from each other and from the remaining portions of said structure.

3. In a locomotive, an underframe structure including a rigid boiler saddle and an expansion plate bracket spaced forwardly of said saddle, 80 and a main exhaust steam pipe positioned at least partially between said saddle and said bracket and spaced from both and from the remaining portions of said structure.

4. A locomotive underframe structure including valve chambers, a rigid boiler support and an expansion plate bracket positioned forwardly of said support, and main exhaust steam passages extending inwardly and upwardly from said chambers and between said support and bracket, 85 said passages being spaced from each other and the remaining portions of said structure.

5. In a locomotive underframe structure, a front deck, pump brackets projecting upwardly on each side thereof, and an expansion plate bracket 90 extending between said pump brackets.

6. A locomotive underframe integral structure comprising a front deck member, pump brackets projecting upwardly on each side thereof, and an expansion plate bracket extending between 95 said pump brackets and bracing the same.

7. In a locomotive underframe structure, spaced rigid boiler saddles, and an exhaust steam passage positioned at least partially between said saddles and spaced throughout its length there-100 from and from the remaining portions of the structure.

8. A locomotive integral underframe structure including spaced rigid boiler saddles, valve chambers at each side of the structure, and exhaust 105 steam pipes extending inwardly and upwardly from said chambers between said saddles and spaced throughout their lengths from the remaining portions of the structure.

9. In a locomotive underframe structure, a 110 transverse laterally projecting beam-like element, main steam cylinders and valve chambers supported by said element and spaced from the underframe, a boiler support, and exhaust steam pipes extending inwardly and upwardly from said 115 chambers and spaced throughout their lengths from said support and the remaining portions of the structure.

10. In a locomotive, an underframe structure including valve chambers and a boiler saddle, 120 a smokebox supported by said saddle, and exhaust steam passages extending from said chambers into said smokebox and spaced throughout their lengths from each other and from said structure, and an inverted V-shaped exhaust nozzle 125 inside said smokebox and connecting with said passages, said passages and nozzle having bolting flanges on their corresponding ends receiving the lower wall of said smokebox between them and forming air tight joints therewith.

11. In a locomotive, an underframe structure including valve chambers and a boiler saddle, a smokebox supported by said saddle, said smokebox having an opening in its lower wall spaced from said saddle, exhaust steam passages extending from said chambers through said opening and spaced throughout their lengths from said saddle and said member and having bolting flanges on their upper ends, and a plate secured over said opening and having a portion shaped to form air tight joints with said flanges and depressed portions adapted to permit expansion and contraction of said passages without unduly straining said plate.

12. In a locomotive underframe structure, 130

- valve chambers, a boiler support, and exhaust steam passages extending inwardly from said chambers at the level of said support and then upwardly, said passages comprising separately 5 formed pipe sections bolted to said chambers and spaced throughout their lengths from each other and the remaining portions of said structure.
13. In a locomotive, an underframe structure including valve chambers at the sides thereof 10 and a boiler support, a smokebox supported by said support, and pairs of exhaust passages extending from said chambers into said smokebox and spaced throughout their lengths from the remaining portions of said structure, each of said 15 pairs including a pair of separately formed U-shaped pipes bolted to one of said chambers, and a three-way pipe section, the lower legs of said section connecting with the inner ends of said pair of U-shaped pipes, and the upright leg 20 thereof leading into said smokebox and making an air tight joint with the lower wall thereof.
14. In a locomotive, an underframe structure including a boiler support, valve chambers, exhaust steam pipes extending inwardly from said 25 chambers and spaced throughout their lengths from the remaining portions of the structure and from each other, and a valve gear bracket projecting from said pipes, and an exhaust nozzle having leg parts secured to said pipes and bracing the same.
15. In a locomotive, an underframe structure including a boiler support and valve chambers, a smoke box supported by said boiler support, and pairs of exhaust steam pipes extending from said 35 chambers to said smoke box, each of said pairs being spaced from the other and from the remaining portions of said structure and being supported solely by the lower wall of said smoke box and the associated chamber.
16. In a locomotive, an underframe structure including a rigid boiler support, a smoke box thereon, valve chambers positioned longitudinally of said support in the direction of the end of said smoke box, and main exhaust passages extending inwardly from said chambers beneath said smoke box and then upwardly and spaced throughout their lengths from each other and the remaining portions of the structure. 80
17. In a locomotive, an underframe structure including valve chambers and a boiler saddle, a smoke box supported by said saddle, and exhaust steam passages extending from said chambers into said smoke box and spaced throughout their lengths from each other and from said structure, and an exhaust nozzle extending within said smoke box and having legs secured to and bracing said passages. 85
18. In a locomotive, an underframe structure including valve chambers at the sides thereof and a boiler support, a smoke box supported by said saddle, pairs of exhaust passages extending from said chambers into said smoke box and spaced throughout their lengths from said structure, each of said pairs including sections extending inwardly at the level of said support, and an exhaust nozzle extending within said smoke box and having legs connecting with and bracing said sections. 90
19. In a locomotive, an underframe structure including a valve chamber and a boiler support, exhaust passages extending inwardly from said chamber and spaced from each other and the remaining portions of the structure, and a valve gear bracket on one of said passages, the passages comprising each pair merging in an exhaust outlet whereby said passages mutually brace each other. 100
